BUTTON BLANK SLICING AND GRINDING
MACHINE

Warren E. Knott, Federalsburg, Md.

Application June 15, 1940, Serial No. 340,825

15 Claims.

(Cl. 79—15)

My invention is a novel machine for slicing and grinding short lengths of pearl cut from shells by means of tubular saws in the usual manner to form button blanks, said lengths being irregular but usually somewhat greater than the thickness of a plurality (three or four) of finished buttons, said short lengths being operated on by the machine to slice same into sections each forming a button blank of substantially standard size suitable for subsequent operation thereon in a button finishing machine.

The principal object of my invention is to provide a novel and efficient machine whereby the short lengths may be fed by an operator into peripheral pockets in a rotatable blank carrying disk, which disk carries same around to and past a gang saw rotatably mounted in the machine, which saw severs the short lengths into button blanks of desired size, whereupon the severed blanks are discharged from the machine.

A further object of my invention is to provide a machine of the above type in which the blank carrying disk may be readily swung aside as a unit from the gang saw, and said saw replaced by a tool having spaced grinding wheels which cooperate with the blank carrying disk to grind the end faces of the sliced sections in places substantially normal to the longitudinal axes of the blanks, said grinding attachment being particularly adapted for use in event the end faces of the short lengths to be sliced are not initially substantially normal to the axes thereof prior to the slicing operation, but the end faces are irregular to a degree which would interfere with the proper finishing of the sliced sections in a button finishing machine.

Other minor objects of the invention will be hereinafter set forth.

I will explain the invention with reference to the accompanying drawings which illustrate several practical embodiments thereof to enable others familiar with the art to adopt and use the same, and will summarize in the claims, the novel features of construction, and novel combinations of parts, for which protection is desired.

In said drawings:

Fig. 1 is a top plan view of the machine arranged to slice the short lengths of pearl into sections forming button blanks.

Fig. 2 is a longitudinal vertical section on the line 2—2, Fig. 1.

Fig. 3 is a reduced plan view of the disk end of the machine, showing the supplemental frame which carries the button disk swung laterally of the main frame of the machine to permit mount-

ing of the grinding tool in place of the gang saw in the machine, or vice versa.

Fig. 4 is an enlarged vertical section through the blank carrying disk and the associated grinding tool.

Fig. 5 is a plan view showing the strap for retaining the blanks in the recesses of the blank carrying wheel, and to hold the blanks from rotating, when using the gang saw.

Fig. 6 is a plan view similar to Fig. 5 showing a modified strap used to hold the blanks in the blank carrying wheel and to hold the blanks from rotating, when the grinding tool is mounted in the machine.

As shown, the machine preferably comprises a frame consisting of base 1 having uprights 2, 3, 4 and 5 at the corners thereof connected at their upper ends by horizontal members 6, 7, 8 and 9, and by intermediate horizontal members 10, 11, 12 and 13, spaced from and parallel with the upper frame members 6 to 9. Preferably uprights 3 and 4 at the rear end of the frame are spaced closer together than uprights 2 and 5 at the front end thereof.

Frame member 7 at the front end of the frame is provided with an inward horizontal extension 7a disposed midway between uprights 2 and 5 and provided with a bearing 7b for a vertical shaft 14 which carries the gang saw or grinding tool hereinafter described. Frame member 11 below member 7 is similarly provided with an extension 11a carrying a bearing 11b receiving the lower end of shaft 14, a collar 14a being provided on said shaft engaging the underside of extension 7a to prevent axial movement of said shaft in its bearings. On shaft 14 is removably mounted a head 32 above bearing 7b carrying a circular gang saw which in the embodiment shown in Fig. 2 consists of two spaced circular saws 33 and 34 of thin metal (about .015 of an inch in thickness). Frame member 9 at the rear end of the frame is provided with a bearing 9a for a vertical shaft 15 having a collar 15a thereon engaging the upper end of the bearing, and fixedly secured to the lower end of shaft 15 is a beveled gear 16 having its hub engaging the lower end of bearing 9a to prevent axial movement of shaft 15 in said bearings.

At the upper ends of shafts 14 and 15 are belt pulleys 21 and 22 or the like respectively around which runs a belt 23. Beveled gear 16 meshes with a beveled gear 17 on a horizontal shaft 18 mounted in brackets 19 and 20 extending upwardly from the frame member 13 disposed below frame member 9. On shaft 18 is a belt pulley

24 opposite a pulley 25 on the shaft of an electric motor 26 mounted on an arm 13a projecting from the frame member 13 at the rear end of the machine, a belt 27 running around pulleys 24 and 25, whereby when motor 26 is actuated the shaft 14 of the gang saw or grinding tool will be rotated at a rapid rate (about 7,000 R. P. M.) owing to the arrangement and sizes of pulleys and gears. Any other convenient source of power might be substituted for the electric motor 26.

On shaft 18, adjacent upright 3, is a worm 28 meshing with a worm gear 29 extending upwardly through an opening in frame member 13, said worm being mounted upon a shaft 30 journaled in brackets 10a and 10b extending from the frame member 10, collars 30a and 30b on shaft 30 maintaining same against axial movement. Shaft 30 is thus also rotated by motor 26, but at a much reduced speed (about $\frac{3}{4}$ R. P. M.) owing to the interposed worm and gear connections between the shafts 18 and 30. Shaft 30 terminates within the frame of the machine and carries on its inner end a head 31 having a non-circular socket 31a therein for the purpose hereinafter described.

Horizontally disposed at the front end of the frame is a plate 35 of substantially circular shape and of diameter substantially equal to that of the blank carrying disk hereinabove referred to, the upper face of plate 35 being spaced below the lower saw 34 a distance approximately equal to the distance between the spaced saws 33 and 34. Plate 35 has an axially disposed bearing 36 depending from its underside adapted to receive a shaft 37 which rotates the blank carrying disk seated upon the top of plate 35.

Extending laterally from the underside of plate 35 are arms 36 and 37, having split clamps 36a and 37a at their outer ends adapted to embrace the uprights 2 and 5 of the frame respectively, as shown in Fig. 1, said brackets preferably resting upon the top of frame member 7 as shown in Fig. 2. Directly below the arms 36 and 37 is a second set of arms 38 and 39 extending from the lower end of plate extension 36 and also having split clamps at their outer ends likewise embracing the uprights 2 and 5, said arms preferably resting upon the top of frame member 11 disposed directly below frame member 7, whereby the plate 35 will be rigidly supported in fixed elevation with respect to the saws 33 and 34. When however the split clamps engaging one upright, such as 5, are removed and the split clamps engaging the other upright 2 are loosened, plate 35 and the elements carried thereby may be swung laterally of the main frame as indicated in Fig. 3 for the purpose hereinafter described.

Mounted upon the upper end of shaft 37 is a blank carrying head of diameter substantially equal to that of plate 35 and preferably consisting of an inner disk 40, a lower disk 41, upper disk 42, and a hub member 43 secured together by means of screws 44 or the like, said hub being fixed by pin 45 or the like to shaft 37. The lower disk 41 contacts directly with the top of plate 35. In the periphery of the disk carrying head 40, 41, 42 is an upper slot 40a (Fig. 2) adapted to receive the upper circular saw 33, and a lower slot 40b adapted to receive the lower circular saw 34, which saws enter said slots for a depth exceeding the diameters of the button blanks B as clearly indicated in Figs. 1 and 2. For convenience of manufacture, the slots 40a and 40b may be formed in the upper and lower

faces of the intermediate disk 40 before the members 41, 42 and 43 are secured together. The upper face of the upper disk 42 of the head is spaced from the upper face of the upper saw 33 a distance approximately equal to the distance between the spaced saws 33 and 34.

In order to impart rotation to the blank carrying head 40, 41, 42, a worm gear 55 is mounted on the lower end of shaft 37 with its hub engaging the lower end of bearing 36, said worm gear being disposed in the horizontal plane of the shaft 39; said gear 55 meshing with a worm 56 mounted on a horizontal shaft 57 journaled in brackets 58 and 59 extending from the lower arm 33 (Fig. 2) of plate 35, said shaft 57 being in axial alignment with shaft 30 and carrying collars 60 and 61 to prevent axial movement thereof in its bearings. The end of shaft 57 adjacent head 31 has a non-circular portion 57a directly engaging the non-circular recess 31a in head 31, whereby shaft 57 when in normal position will be driven directly by shaft 30. By the above arrangement however, when the plate 35, and the elements carried thereby, are swung away from the main frame of the machine, as indicated in Fig. 3, shaft 57 will be swung away from the shaft 30 and the non-circular portions 57a and 31a of said shaft members will merely pass out of engagement during the swinging movement. When however the parts are restored to normal position, shown in Fig. 1, the parts will reassume the positions shown in said figure.

In the periphery of the button carrying head 40, 41, 42, is a series of closely adjacent substantially circular recesses 40c of diameter slightly greater than that of the pearl blanks B, said recesses extending more than 180° in arcuate length. When the blanks B (Fig. 2), which are approximately equal in length to the combined thickness of the head 40, 41, 42, are inserted in the recesses 40c by the operator as the head 40, 41, 42 is revolving, the blanks will be carried around by rotation of the head and engaged by the saws 33 and 34 which will slice the blanks into three sections of approximate equal thickness, the operator being seated at the front end of the frame and placing blanks from a bin (not shown) into the recesses 40c as the head revolves in the direction of the arrow shown in Fig. 1.

Plate 35 is cut away as at 35a (Fig. 2) below the saws 33 and 34 for the purpose hereinafter described, and in order to retain the button blanks B firmly in their recesses 40c with their side walls in direct frictional contact with the inner walls of said recesses 40c, a metal strap 46 (Figs. 1, 2 and 5) is provided flexed around the periphery of the blank carrying head 40, 41, 42 at the side adjacent the saws 33 and 34, said strap having parallel slits 46a and 46b (Fig. 5) thereto to permit the saws 33 and 34 to pass therethrough and enter the grooves 40a and 40b in the periphery of the head in order to slice the blanks B held in the recesses 40c. As shown, strap 46 yieldably engages the exposed peripheries of the blanks B in their recesses 40c as they come into engagement therewith, the strap 46 having heads 47 and 48 at its ends, said heads having bearings journaled on studs 49 and 50 respectively (Fig. 1) mounted on arms 51 and 52 extending laterally from the underside of the plate 35 and terminating adjacent the split clamps 36a and 37a, respectively. Springs 53 and 54 are connected respectively with the arms 51 and 52 and their respective heads 47 and 48.

tend to swing the heads so as to maintain a constant tension on band 46, as illustrated in Fig. 1.

By the above construction, as the operator places the blanks B in the recesses 40c of the blank carrying head 40, 41, 42, said blanks initially rest directly upon the underlying plate 35 and are carried around by rotation of the head in the direction of the arrow (Fig. 1) until they come into contact with the yieldable strap 46, whereupon the blanks are forced into direct frictional contact with the inner walls of recesses 40c and are thus carried over the gap 35a of plate 35, and to the gang saw 33, 34, which is rapidly rotating in the opposite direction. After the blanks B have been thus sliced by the saws 33 and 34, the severed sections will subsequently be ejected from the recesses 40c.

Slots 46a and 46b of strap 46 are of slightly greater width than the thickness of saws 33 and 34, and since the walls of said slots engage the upper and lower faces of the saws respectively, said slots will, to a large extent, prevent warping or flexing of the saws during cutting operation, thus permitting use of very thin saws without buckling. In order to further enhance the rigidity of the saws, a rigid arm 62 is provided secured by bolts 63, or the like, to frame member 6, said member having at its outer ends slots similar to slots 46a and 46b of strap 46 into which the peripheral portions of the saws 33 and 34 enter, the end of member 62 terminating adjacent the strap 46 and serving as an additional means to prevent warpage or flexing of the rapidly rotating saws 33 and 34 of thin material. When the saws 33 and 34 are being placed on or removed from shaft 14 however it is necessary to remove or to swing the member 62 out of engagement with the saws during such removal or replacement.

After slicing the short lengths B of pearl as above described by the saws 33 and 34, it sometimes occurs that certain of the end sections thus cut will have a face which is not substantially normal to the axis of the section owing to the nature of the shell, and such blanks or sections could not be successfully used in the subsequent blank finishing machine. It is therefore necessary to grind such irregular blanks or sections (which in practice are found to comprise only a small percentage of the sliced blanks) in the same machine, by merely substituting a grinding tool in place of the gang saw, and making slight further substitution of parts in the machine. For the purpose of effecting such changes, the split clamps of the arms of plate 35 are entirely removed from upright 5, while the split clamps which engage upright 2 are merely loosened, and plate 35 together with the elements carried thereby is swung bodily as indicated in Fig. 3 away from the front end of the frame to disengage the blank carrying head 40, 41, 42 from the saws 33 and 34. The member 62 is then removed from frame member 6, and the collar 14a of shaft 14 loosened and the entire shaft 14 is disengaged from the machine for lifting vertically. The head 32 carrying the saws 33 and 34 is then removed from shaft 14, and a head 64 (Figs. 3 and 4) inserted in place thereof on said shaft, said hub carrying spaced grinding wheels 65 and 66 of substantially the same diameter as the saws 33 and 34, and the distance between the faces of the grinding wheels 65 and 66 being substantially equal to the normal thickness of the blank sections B' previously cut by the saws 33 and 34 from the blank B. Shaft 14

with head 64 is then reinserted in the machine, the upper surface of the lower grinding wheel 66 being disposed at substantially the level of the upper surface of plate 35, and the plate 35 with a modified strap 67 and head 68, is restored to normal position shown in Fig. 1. In place of strap 46 a strap 67 (Fig. 6) is inserted in the same manner as the strap 46, but in strap 67 the major portion thereof is of a thickness adapted to fit between the grinding wheels 65, 66. A blank carrying head 68 is also used in place of head 40, 41, 42, said head 68 being of less thickness than the normal thickness of the blank section B' (Fig. 4), and said head having series 15 of blank holding recesses 68a therein (Figs. 3 and 4) similar to recesses 40a of head 40, 41, 42, whereby as the irregular blank sections B' are placed in the recesses 68a by the operator (when the parts are in normal position), the blanks 20 will be carried around the disk or head 68 held squarely against the inner walls of the recesses 68a by the strap 67, as they come into contact therewith, and the blanks B' will thus be fed between the grinding wheels 65, 66 whereby the 25 irregular faces of said blanks will be ground to the desired thickness and uniformity before being passed along to the button finishing machine. As previously stated, only a small portion of the sliced sections B' of blanks B will require the above grinding treatment, and by slight alteration or substitution of parts, the same machine may be utilized to both slice and grind the blanks.

I do not consider my invention limited to the exact machine shown in the drawings, for obviously changes may be made therein within the scope of the claims.

I claim:

1. In a machine for operating on button blanks, a driven shaft; a rotatable tool mounted thereon; a disk-shaped head rotatably mounted adjacent the tool; means for rotating said head; the peripheral portions of said head and tool being normally disposed in overlapping relation; said head having recesses in its periphery each adapted to partly encircle a blank and to carry same around to and past the said tool; and a stationary flexible band yieldingly contacting the periphery of the head and the exposed portions of the series of the blanks in way of the tool to hold the blanks in frictional contact with the walls of the recesses as same approach and are operated upon by the tool.

2. In a machine as set forth in claim 1, said head being horizontally disposed; and a stationary member supporting said head and supporting the blanks in the recesses during rotation of the head.

3. In a machine as set forth in claim 1, said head being horizontally disposed; and a stationary member supporting said head and supporting the blanks in the recesses during rotation of the head, said member being cut away throughout the overlapping portions of the head and tool.

4. In a machine as set forth in claim 1, a support for said driven tool shaft; a frame carrying the head and the flexible band; means swingably mounting the frame on an axis parallel with and spaced from the axis of the tool for movement to and from an operative position with respect thereto; means for maintaining the frame in normal operative position; and said head rotating means comprising a rotatable member relatively fixedly journaled in the machine and provided with a non-circular socket; means for driving said rotatable member; a shaft section

having a non-circular end journaled in the swingable frame in alignment with said rotatable member and of such dimensions that the non-circular end will enter the non-circular socket when the frame is swung to normal operative position; said non-circular end disengaging from the socket when the frame is swung out of normal position; and means for rotating the head from said shaft section.

5. In a machine for operating on button blanks, a driven shaft; a rotatable tool mounted thereon; a relatively fixed plate mounted beside said tool; a disk-shaped head rotatably mounted on said plate; means for rotating said head; the peripheral portions of said head and tool being normally disposed in overlapping relation; said head having parti-circular recesses in its periphery adapted to partly encircle blanks supported upon the plate and to carry same around to and past the said tool for operation thereon while retained in the said recesses; and elongated arcuate means carried by the fixed plate extending past and engaging the exposed portions of a series of blanks for holding the series in their respective recesses during operation thereon by said tool.

6. In a machine as set forth in claim 5, said blank holding means comprising a flexible strap; and means for yieldably supporting the strap so that the same will conform with the periphery of the head at the zone of the tool for contacting the blanks just prior to and during operation of the tool to hold the same in said recesses.

7. In a machine as set forth in claim 5, said tool comprising spaced circular saws, and said head having spaced peripheral grooves therein each adapted to receive a saw, the overlap of the saws cutting through the said recesses; said blank holding means comprising a flexible strap having spaced slots therein for permitting the saws to enter the peripheral grooves in the head; and means for yieldably supporting the strap so that same will conform with the periphery of the head at the zone of the tool for contacting the blanks just prior to and during operation of the tool to hold the same in said recesses.

8. In a machine as set forth in claim 5, said tool comprising spaced circular saws, and said head having spaced peripheral grooves therein each adapted to receive a saw, the overlap of the saws cutting through the said recesses; and blank holding means comprising a flexible strap having spaced slots therein for permitting the saws to enter the peripheral grooves in the head; a fixed member having spaced slots therein receiving the saws of the gang, the walls of the slots in the strap and fixed member engaging the faces of the saws to prevent buckling thereof; and means for yieldably supporting the strap so that same will conform with the periphery of the head at the zone of the tool for contacting the blanks just prior to and during operation of the tool to hold the same in said recesses.

9. In a machine as set forth in claim 5, a support for said driven tool shaft; a frame carrying the head and the flexible band; means swingably mounting the frame on an axis parallel with and spaced from the axis of the tool for movement to and from a operative position with respect thereto; means for maintaining the frame in normal operative position; and said head rotatting means comprising a rotatable member relatively fixedly journaled in the machine and provided with a non-circular socket; means for

driving said rotatable member; a shaft section having a non-circular end journaled in the swingable frame in alignment with said rotatable member and of such dimensions that the non-circular end will enter the non-circular socket when the frame is swung to normal operative position; said non-circular end disengaging from the socket when the frame is swung out of normal position; and means for rotating the head from said shaft section.

10. In a machine for operating on circular button blanks; a main frame; a drive shaft journaled therein; a driven shaft; means for actuating said driven shaft by said drive shaft; a circular tool mounted on said driven shaft; a fixed plate mounted in the frame adjacent said tool; a disk-shaped head rotatably mounted on said plate; means for driving said head from said drive shaft; the peripheral portions of said head and tool being disposed in overlapping relation, and said head having an annular series of circular recesses in the periphery of less than 360° arcuate length adapted to receive blanks supported on the plate and carry same around to and past the tool for operation thereon while retained in the said recesses; and elongated arcuate means carried by the fixed plate extending past and engaging the exposed portions of a series of blanks for holding the series in their respective recesses during operation thereon by the tool.

11. In a machine as set forth in claim 10, said blank holding means comprising a flexible strap; and means for yieldably supporting the strap so that same will conform with the periphery of the head at the zone of the tool for contacting the blanks just prior to and during operation of the tool to hold same in said recesses.

12. In a machine as set forth in claim 10, said tool comprising a circular gang saw, and said head having spaced peripheral grooves therein each adapted to receive a saw of the gang; the overlap of the saws and head cutting through the said recesses; said blank holding means comprising a flexible strap having spaced slots therein for permitting the saws to enter the peripheral grooves in the head; and means for yieldably supporting the strap so that same will conform with the periphery of the head at the zone of the tool for contacting the blanks just prior to and during operation of the tool to hold same in said recesses.

13. In a machine as set forth in claim 10, said tool comprising a circular gang saw, and said head having spaced peripheral grooves therein each adapted to receive a saw of the gang; the overlap of the saws and head cutting through the said recesses, and said blank holding means comprising a flexible strap having spaced slots therein for permitting the saws to enter the peripheral grooves in the head; a member on the frame having spaced slots therein receiving the saws of the gang, the walls of the slots in the strap and fixed member engaging the faces of the saws to prevent warpage thereof; and means for yieldably supporting the strap so that same will conform with the periphery of the head at the zone of the tool for contacting the blanks just prior to and during operation of the tool to hold same in said recesses.

14. In a machine as set forth in claim 10, a support for said driven tool shaft; a sub-frame carrying the plate having the rotatable head and carrying the elongated arcuate means; means

swingably mounting the sub-frame on an axis parallel with and spaced from the axis of the tool for movement to and from an operative position with respect thereto; means for maintaining the sub-frame in normal operative position; and said head rotating means comprising a rotatable member relatively fixedly journaled in the machine and provided with a non-circular socket; means for driving said rotatable member; a shaft section having a non-circular end journaled in the sub-frame in alignment with said rotatable member and of such dimensions that the non-circular end will enter the non-circular socket when the sub-frame is swung to normal operative position; said non-circular end disengaging from the socket when the sub-frame is swung out of normal position; and means for rotating the head from said shaft section.

15. In a machine for operating on button blanks, a main frame; a driven shaft journaled in said frame; a circular tool mounted on said shaft; a plate mounted on said frame adjacent

5 said tool; a blank carrying head rotatably mounted on said plate and adapted to carry blanks around to and past the tool for operation thereon by said tool; a sub-frame carrying the plate and head; means swingably mounting the sub-frame on the main frame and on an axis parallel with and spaced from the axis of the tool for movement to and from an operative position with respect thereto; a rotatable member relatively fixedly journaled in the main frame and provided with a non-circular socket; means for rotating said rotatable member; a shaft section having a non-circular end journaled in the sub-frame in alignment with the rotatable member and of such dimensions that the non-circular end will enter the non-circular socket when the sub-frame is swung to normal operative position; said non-circular end disengaging from the socket when the sub-frame is swung out of normal position; and means for rotating the head from the said shaft section.

20 WARREN E. KNOTT.
